CLAIM

The ornamental design for a pre-start lubrication system for automotive turbocharger, as shown and described.

DESCRIPTION

FIG. 1 is a front elevational view of a pre-start lubrication system for automotive turbocharger showing our new design;

FIG. 2 is a side elevational view thereof, the opposite side being a mirror image;

FIG. 3 is a top plan view thereof;

FIG. 4 is a rear elevational view thereof;

FIG. 5 is a bottom plan view thereof;

FIG. 6 is a front elevational view of a pre-start lubrication system for automotive turbocharger showing a second embodiment of our new design;

FIG. 7 is a side elevational view of FIG. 6, the opposite side being a mirror image;

FIG. 8 is a top plan view of FIG. 6;

FIG. 9 is a rear elevational view of FIG. 6; and,

FIG. 10 is a bottom plan view of FIG. 6.

FIG. 3

FIG. 1

FIG. 2

FIG. 4

FIG. 5

FIG. 8

FIG. 6

FIG. 7

FIG. 9

FIG. 10
